CLAIM

The ornamental design for a hat, as shown and described.

DESCRIPTION

FIG. 1 is a perspective view of the hat showing my design;

FIG. 2 is a right side elevational view thereof;

FIG. 3 is a left side elevational view thereof;

FIG. 4 is a front elevational view thereof; and,

FIG. 5 is a top plan view thereof.

The broken lines showing a portion of the baseball-style hat in FIG. 1-5 illustrate environmental matter and form no part of the claimed design.
